UNITED STATES PATENT OFFICE.

LEONE S. SHARPS, OF NEW YORK, N. Y.

ADVERTISING DEVICE.

No. 902,840.

Specification of Letters Patent.

Patented Nov. 3, 1908.

Application filed February 6, 1907. Serial No. 355,995.

To all whom it may concern:

Be it known that I, LEONE S. SHARPS, a citizen of the United States, residing in the city of New York, borough of Brooklyn, county of Kings, and State of New York, have invented certain new and useful Improvements in Advertising Devices, of which the following is a full, clear, and exact specification.

10 This invention relates generally to advertising devices and particularly to apparatus intended for the production of an illusion with respect to the formation or manufacture of certain articles of commerce, as will 15 hereafter appear.

The object of the invention is to provide a strong, simple, durable, and comparatively inexpensive device of the character set forth, adapted to produce novel advertising effects.

20 With the foregoing and other objects in view which will appear as the description proceeds, the invention resides in the combination and arrangement of parts and in the details of construction hereinafter described 25 and claimed, it being understood that changes in the precise embodiment of invention can be made within the scope of the following claims without departing from the spirit of the invention.

30 In the accompanying drawings forming part of this specification, Figure 1 is a side elevation of an advertising device constructed in accordance with the invention. Fig. 2 is a side elevation showing the opposite side 35 of the device from that illustrated in Fig. 1. Fig. 3 is a longitudinal, vertical section through the device illustrated in Figs. 1 and 2. Fig. 4 is a plan view of the device. Fig. 5 is a detail view, partly in section, showing 40 one convenient form of mechanism for creating an illusion. Fig. 6 is a detail sectional view taken at a right angle to Fig. 5. Fig. 7 is a detail plan view of the mechanism for automatically throwing out of operation the 45 devices illustrated in Fig. 5. Fig. 8 is a horizontal section through the suction chamber. Fig. 9 is a detail vertical section through a controlling device located in the suction chamber. Fig. 10 is a detail plan view of a 50 pneumatic valve. Fig. 11 is a longitudinal vertical section through a modified form of apparatus.

55 Like reference numerals indicate corresponding parts in the different figures of the drawing.

It may be briefly premised that the embodi-

ment of invention illustrated in Figs. 1 to 10 inclusive is intended particularly for simulating the operation of cutting or forming a perforated music roll, so that when the device is placed in the show window of a music store it will provoke the curiosity of passers-by by counterfeiting the action of forming a music roll. To this end the device is provided with an endless belt of paper which is 60 supposed to represent the music roll before it has been perforated; a perforated strip of paper which forms a continuation of the blank strip of paper; mechanism out of contact with the two strips of paper for creating 65 the illusion of perforating one of the sheets, suitable mechanism for moving the perforated sheet in one direction or the other; and other details of construction to be more fully set forth hereafter.

75 Referring to Figs. 1 and 2, the reference numeral 1 indicates the body of the apparatus, which is in the form of a rectangular box supported upon legs 2. The means for driving the various parts of the apparatus 80 preferably consist of an ordinary electric motor 3.

As shown in Fig. 2, the motor 3, by means of a belt 4, drives a large belt wheel 5 fixed on a shaft 6, which extends transversely 85 through the apparatus. The shaft 6, by means of a belt 7, drives a belt wheel 8 fixed on a shaft 9. The shaft 9, by means of a sprocket wheel 10 fixed thereon, drives a sprocket chain 11, which in turn drives a 90 sprocket wheel 12 fixed on a shaft 13. The shaft 13, at its opposite end, drives a sprocket wheel 14, which is adapted to be clutched and unclutched from the shaft, as will hereafter appear. Sprocket wheel 14, through a 95 sprocket chain 15, drives sprocket wheels 16, 17. The sprocket wheel 16 is fixed on the shaft 18 of a roll 19. Extending around the roll 19 is an endless strip of blank paper or other suitable material 20 which, as shown in 100 Fig. 3, extends at its opposite end around an idle roll 21. Through the chain of mechanism described, it will be seen that the endless strip 20 is normally driven in the direction of the arrow from the motor 3, and that 105 the movement of the strip 20 can be stopped when desired, by unclutching the sprocket wheel 14 from the shaft 13, as will hereafter appear.

The mechanism for creating an illusion 110 with respect to the endless strip 20 so as to simulate the operation of punching holes in

the said strip, preferably is operated by the sprocket wheel 17, which is mounted on a shaft 22. The shaft 22, as shown in Figs. 5 and 6, is provided with a cylinder 23, from the periphery of which a number of pins 24 project in radial directions. The radial pins 24, during the operation of shaft 22 and cylinder 23, are adapted to engage and raise at different times a number of gravity-actuated dummy plungers 25, which are loosely mounted for vertical movement in any suitable manner in a boxing 26, which covers and conceals one end of the endless strip 20, as shown in Fig. 1. As soon as one of the plungers 25 has been raised by one of the pins 24, and said pin moves out of engagement with the plunger, said plunger drops by gravity into its lowest position. The plungers 25 serve to create the effect of punches acting on the strip 20, and thus serve to simulate the operation of punching holes in said strip, although it will be seen that this illusion mechanism is out of engagement with the strip or moving surface 20. Any number of plungers 25 can be employed, and the pins 24 preferably are so arranged on the cylinder 23 as to raise different plungers at different times. It will be understood that when the sprocket wheel 14 is unclutched from the shaft 13, as will hereafter appear, the operation of the sprocket chain 15, and consequently the operation of the plungers 25 and endless strip or surface 20 will be simultaneously stopped.

The reference numeral 27 indicates an ordinary perforated music sheet which is wound at one end, as shown in Fig. 3, upon a roll or spool 28 fixed on a shaft 29 journaled in the machine frame. From the spool 28 the perforated sheet or surface 27 passes around an idle roll 30, as well as the roll 31 mounted loosely on the shaft 13. From the roll 31 the perforated surface or strip 27 is wound around or connected with a spool 32 suitably connected with the machine frame. It will be observed that the idle roll 30 in Fig. 3 is disposed in proximity to the roll 19, and that both of said rolls are disposed under the boxing 26, whereby the endless surface 20 and the perforated surface 27 create the illusion of a single surface moving continuously under the boxing 26 and being perforated by means of the plungers 25.

The means for driving the spool 32 so as to wind the perforated strip or surface thereon preferably comprises a belt 33, which is operated by a shaft 9, and drives at its opposite end a gear wheel 34, which is mounted upon a lever 35 pivoted at 36. The gear wheel 34 meshes with a gear 37, which in turn meshes with a gear wheel 38, mounted upon the shaft of the spool 32 so as to drive the same. When it is desired to rewind the perforated strip or surface 27 in a rearward direction on to the spool 28, the lever 35 is operated as

will hereafter appear, to throw the gear wheel 34 out of mesh with the gear wheel 37.

The mechanism for rewinding the perforated sheet 27 onto the spool 28 after it has been completely wound on to the spool 32 preferably comprises a sprocket chain 39, which is driven by a sprocket wheel 40 fixed on the shaft 6 as shown in Fig. 1. The sprocket chain 39 drives a sprocket wheel 41, which is formed with two sprocket portions so that it in turn drives a sprocket chain 42 for a purpose hereinafter to be described. The sprocket wheel 41 is journaled upon a lever 43, which is fulcrumed at 44 upon the machine frame. The up and down movement of the free end of the lever 43 is limited by an ordinary traveler bracket 45. When the lever 43 is raised in the manner hereinafter described, the sprocket chain 39 meshes with a sprocket wheel 46, which is mounted on the shaft 29 of the rewinding spool 28 so as to rewind the perforated sheet 27. At the same time that the sprocket chain 39 is raised by the lever 43 into engagement with the sprocket wheel 46, the lever 35, which is connected with the lever 43 by means of a link 47 is rocked so as to disengage the sprocket wheel 34 from the sprocket wheel 37.

For the purpose of stopping the operation of the endless strip or surface 20 and the plungers 25 while the perforated strip or surface 27 is being rewound in a backward direction, the following mechanism is employed. The link 47 which is connected with lever 43 at 48, is extended upward and is provided with a lug or projection 49 shown in Figs. 1 and 7. When the link 47 is raised by the lever 43, the lug 49 engages a lateral arm 50, mounted on a shaft 51, which is journaled in brackets 52 on the machine frame. The opposite end of the shaft 51 projects into proximity with the sprocket wheel 14 and is provided with a lateral pin 53 indicated by dotted lines in Fig. 1, and by full lines in Fig. 7, so that when the shaft 51 is rocked by the upward movement of the lever 43 and link 47, the pin 53 presses against the sprocket wheel 14 and moves it out of engagement with any well known and suitable form of clutch 54 on the shaft 13, so as to throw the sprocket chain 15 out of operation and stop the movement of the strip 20 and plungers 25 during the rewinding of the perforated strip or surface 27. When the shaft 43 and link 47 are lowered, as will hereafter appear, to throw the sprocket wheel 34 into engagement with the sprocket wheel 37 and again begin the forward winding of the perforated strip 27, a spring 55 throws the sprocket wheel 14 into engagement with the clutch 54 and thus restarts the operation of the strip 20 and plungers 25.

In order to prevent the sprocket chain 39 on the lever 43 from sagging out of engagement with the sprocket wheel 46, a second

idle sprocket wheel 56 is journaled on a stud on the lever 43 as shown in Fig. 1.

The mechanism for raising and lowering the lever 43 so as automatically to move the 5 perforated strip 27, first in a forward direction and then in a backward direction, preferably is constructed as follows: The numeral 57 in Figs. 8 and 9 indicates a suction chamber which is in the form of a 10 rectangular box extending along the bottom of the machine frame, as shown in Fig. 3. Communicating with one end of the suction chamber 57 through perforations 58 is an ordinary form of suction bellows 59, which 15 is operated or pumped by means of a link 60 connected, as shown in Fig. 1, in an eccentric manner with the sprocket wheel 40 so that the rotation of said sprocket wheel will alternately expand and collapse the bellows 59 20 whereby to exert suction on the suction chamber 57. Connected with the opposite end of the suction chamber 57 by means of a perforation 61, is an auxiliary suction device 62, which consists preferably of an ordinary 25 bellows held normally in expanded position by means of a spring 63, which may be of elliptical or othersuitable form. The suction in the suction chamber 57 collapses the auxiliary suction device 62, but should the suction 30 in the chamber 57 fall below a certain strength for any reason, the spring 63, by expanding the auxiliary device 62, will serve temporarily to increase the suction in the chamber 57.

Located between the bellows 59 and the auxiliary device 62 is a bellows 64 which is normally in communication with the atmosphere through a wind passage 65 which extends upward through one wall of the chamber 57, and has a lateral branch opening into a valve seat 66 in the upper side of the suction chamber 57. It will be apparent that as long as the bellows 64 is in communication with the atmosphere, said bellows will be in 40 an expanded condition, but should the communication of said bellows with the atmosphere be shut off, and should said bellows 64 be thrown into communication with the suction chamber 57, said bellows will be collapsed, and through a link 67 shown in Fig. 1, 45 will raise the lever 43 as previously described. The means for alternately throwing the bellows 64 into communication with the atmosphere and with suction chamber 57 is preferably constructed as follows: 50 Mounted in the suction chamber 57 is a controlling device 68 which is formed with an air chamber 69, as shown in Fig. 9, covered by a flexible diaphragm 70. Resting upon 55 the flexible diaphragm 70 is the stem 71 of a valve 72. The air chamber 69 in the controlling device 68 is adapted to be connected with the atmosphere by an air pipe 73, which leads across the lower end of the 60 suction chamber 57, and is provided with an

exit or terminal indicated at 74 in Fig. 10. The terminal 74 is adapted to be opened or closed by means of a slide valve 75, which is provided with a slot 76, which may be of any suitable and well known shape and into which projects a crank terminal 77 of a shaft 78 journaled on the side of the machine frame, and provided at its upper end, as shown in Fig. 4, with a crank portion 79, which extends across the perforated sheet or 75 surface 27 and is adapted to be engaged and partially rotated by means of a block 80 of wood or other material pasted or otherwise secured on the perforated strip 27, it being understood that two plugs 80 are employed, 80 one on the forward end and the other on the rear end of the strip 27. The operation of this part of the device is as follows: When the strip 27 is moving in a forward direction, the slide valve 75 is closed so the atmosphere 85 can have no communication with the air chamber 69 of the controller 68. Consequently the valve 72 is in the position illustrated in Fig. 9, and the atmosphere can communicate through the valve seat 66 and 90 air passage 65 with the bellows 64, which is expanded, thus holding the lever 43 in lowered position and causing the sprocket wheel 34 to operate the sprocket wheel 37 and wind the perforated sheet 27 forward. As 95 soon as the perforated sheet 27 has been wound almost entirely on the spool 32, the plug 80 in Fig. 4 strikes the crank portion 79 of the shaft 78 and causes the lower crank portion 77 of said shaft to open the slide 100 valve 75, thus permitting the atmosphere to rush in through the opening through the pipe 73, leading to the air chamber 69 in the controller 68. As this air chamber is located in the suction chamber 57, the entrance of the 105 atmosphere beneath the diaphragm 70 causes said diaphragm to bulge or expand upward, thus raising the valve 72 and causing it to be pressed against the upper end of the valve seat 66 above the air passage 65 110 leading to the bellows 64. This raising of the valve 72 shuts off the atmospheric communication with the air passage 65 and throws said air passage 65 into communication with the suction chamber 57, whereby 115 the bellows 64 is collapsed so as to raise the lever 43 and thus automatically throw the spool 28 into operation, and the spool 32 out of operation to rewind the strip 27 in a backward direction, and at the same time throwing out of operation the plungers 25 and the blank strip 20 by disengaging the sprocket wheel 14 from the shaft 13. The parts remain in this position until the strip 27 has been almost completely wound on the spool 28, at which time the plug 80 at the forward 120 end of the strip 27 restores the crank portion 79 of shaft 78 to its original position to close the slide valve 75 and again cause said perforated strip to be wound forward. It will be 125 130

understood that the chamber 69 is provided with an ordinary pinhole vent leading into the suction chamber 57, so that when the valve 75 is closed, the pressure in the chamber 69 will be reduced. As this pinhole vent is old and well known in the art, specific illustration thereof is unnecessary.

For the purpose of dropping little pieces of paper from the lower end of the machine to represent the cuttings from the perforated roll 27, a hopper 81 is placed in the machine frame as shown in Fig. 3, in the form of a drawer which can be drawn outward when the hopper is empty. A valve 82 held closed by a spring 83 is adapted to be periodically opened by means of a cam 84, mounted on the shaft 9. In order to provide certain dummy mechanism which will operate on the front face of the device to give it a complicated appearance and to provide a large number of moving parts to attract attention, the sprocket chain 42 shown in Fig. 1 is caused to rotate a shaft 85 shown in Fig. 3, which shaft is provided with a crank portion 86 adapted, through a link 87, to rock an arm 88 on a shaft 89. The shaft 89, as shown in Fig. 2, is provided on the outside of the machine with a reciprocating lever 90, which reciprocates the pistons 91 of the dummy cylinders 92. The belt wheel 5 is also utilized through a link 92^a to operate the piston 93 of the dummy cylinder 94. A pseudo-electric connection 95 leads to the guiding means for the plungers 25 so as to create the effect of an electrical operation of these parts.

In the modified construction shown in Fig. 11, the device is intended to create the illusion of forming candy or other material, such, for example, as chocolate balls or drops. In this case the belt 20' is driven in any suitable manner from the motor 3. Pasted to the surface of the belt in any suitable manner is granulated or other material adapted to represent chocolate powder or shavings and the like. The forward end of the belt 20' passes under the boxing 26, which is provided with plungers or other dummy mechanism 25', operated in any suitable manner by the motor 3. The belt 27' in this instance is endless, and is driven in any suitable manner. An endless conveyer 100, provided with pockets or receptacles 101, is adapted to raise dummy chocolate drops or other pieces of candy or other material from a hopper 103 and deposit them under the boxing 26 upon the belt 27'. From the forward end of the belt 27' the dummy articles drop on to a deflector 104 and fall into a receptacle 105, in which a deflector 106 deposits them on an endless belt or conveyer 107, which reconveys them to the hopper 103. The belts for driving the various mechanism are all clearly indicated in dotted lines, and as these belts may be arranged in various different ways, a specific description thereof is deemed to be

unnecessary. The reference numeral 108 indicates a hopper which is supposed to be filled with powdered chocolate or other material to be fed on to the belt 20'.

The apparatus of the present invention is strong, simple, durable, and inexpensive in construction, as well as thoroughly efficient in operation.

What is claimed is:

1. An advertising device having a plurality of movable surfaces combined to appear as a continuous surface, and mechanism out of engagement with said surfaces for creating an illusion with respect to one of said surfaces. 75

2. An advertising device having two movable surfaces combined to appear as a continuous surface, and mechanism out of engagement with said surfaces for creating an illusion with respect to one of said surfaces. 80

3. An advertising device having a plurality of movable surfaces presenting different appearances and combined to appear as a continuous surface, and mechanism out of engagement with said surfaces for creating an illusion with respect to one of said surfaces. 85

4. An advertising device having a plurality of movable surfaces combined to appear as a continuous surface, and means for moving one of said surfaces in either direction without operating the other surface. 95

5. An advertising device having a plurality of movable surfaces, means for moving one of said surfaces in only one direction, and means for moving the other surface in two directions. 100

6. An advertising device having a plurality of movable surfaces, means for moving said surfaces in one direction, and means for stopping one of said surfaces and moving another surface in a reverse direction. 105

7. An advertising device having a plurality of movable surfaces, means for moving said surfaces in one direction, and means for automatically stopping one surface and reversing the movement of the other surface. 110

8. An advertising device having a plurality of movable surfaces and automatic means for stopping and starting one surface and for reversing the movement of another surface. 115

9. An advertising device having a plurality of movable surfaces, dummy mechanism, and means for stopping the dummy mechanism and one of said surfaces without stopping another of said surfaces. 120

10. An advertising device having a plurality of movable surfaces, dummy mechanism, and automatic means for stopping the dummy mechanism and one surface and for reversing the movement of another surface. 125

11. An advertising device having a plurality of movable surfaces, dummy mechanism, and automatic means for stopping and starting the dummy mechanism and one sur- 130

face, and for reversing the movement of another surface.

12. An advertising device having a plurality of movable surfaces, means for creating 5 an illusion with respect to one of said surfaces and pneumatic means for controlling the operation of said surfaces.

13. An advertising device having movable surfaces and pneumatic means for stopping 10 and starting one surface and for reversing the movement of another surface.

14. An advertising device having movable surfaces, separate gearing for operating each surface, and means for automatically stopping 15 the gearing of one surface and reversing the gearing of another surface.

15. An advertising device having an end-

less surface, a second surface, a spool for each end of the second surface, dummy mechanism, a sprocket chain for operating the endless surface and dummy mechanism, reversible gearing for operating said second surface, and pneumatic means for automatically reversing the gearing of the second surface, and stopping the sprocket chain which 25 operates the endless surface and dummy mechanism.

In testimony whereof, I have hereunto set my hand in the presence of two subscribing witnesses.

LEONE S. SHARPS.
